WILLIAM C. TREGONING, OF WAUWATOSA, WISCONSIN, ASSIGNOR TO CUTLER-HAMMER, INC., OF MILWAUKEE, WISCONSIN, A CORPORATION OF DELAWARE

MOLDED INSULATION ARTICLE

Application filed July 18, 1929. Serial No. 379,225.

This invention relates to improvements in molded insulation articles, and as will appear the invention relates more particularly to improvements in lamp socket casings comprising separable insulating cap and body members of the character disclosed in my copending application filed May 7, 1928, Serial No. 275,768.

An object of the invention is to provide improved means for effecting interlocking engagement and disengagement of the insulating cap and body members with respect to each other.

Another and more specific object is to provide means for insuring against excessive bending of a portion of the insulating casing during assembly or dis-assembly of the cap and body members whereby accidental breakage of the casing is avoided.

Another object is to provide an insulating casing section having a bendable wall portion of normal thickness or strength.

Another object is to provide a lamp socket base having means to accommodate said wall portion upon inward bending thereof.

Other objects and advantages of the invention will hereinafter appear.

The accompanying drawings illustrate an embodiment of the invention which will now be described; it being understood that the invention is susceptible of embodiment in other forms without departing from the scope of the appended claims.

In the drawings, Figure 1 is a perspective view of the molded insulating cap and body members of a lamp socket casing constructed in accordance with my invention, the parts being shown in separated relation.

Fig. 2 is an enlarged top plan view of the body member with a lamp socket base in position, the bendable portion of the wall being shown in normal position.

Fig. 3 is a similar view, with the bendable portion of the wall in depressed relation.

Fig. 4 is a view similar to Fig. 3 showing the cap and body members in partly assembled relation, the cap member being shown in section.

Fig. 5 is a fragmentary perspective view showing the inner surface of the wall of the

body member and the bendable portion thereof.

Fig. 6 is an enlarged fragmentary sectional view on the line 6-6 of Fig. 1, and

Fig. 7 is a top plan view of a modified form of body member.

Referring to the drawings the numeral 10 designates in general a molded insulating cap of substantially the form shown in my application aforementioned. Thus the cap 60 comprises an intermediate bell-shaped portion 11, an interiorly threaded bushing 12 integral therewith, and an integral lower or skirt portion 13. The inner surface of portion 13 is provided with a multiplicity of 65 equally spaced L-shaped or bayonet grooves, each slot including a horizontal arm 14 and a slightly deeper vertical arm 15.

The skirt portion 13 is preferably provided with radial projections 16 alined with the respective arms 15 of the grooves to retain a proper thickness of the insulation wall. Similarly the portion 13 is preferably provided at the lower edge thereof and between the projections 16 with relatively narrow angularly arranged projections 17 to strengthen 75 said edge and to improve the appearance of the cap.

Cap 11 is further provided with an interior annular shoulder 18 against which the upper end of the body portion of the casing is adapted to abut when the parts are assembled, as hereinafter described. A plurality of integral inward projections are provided within the bell shaped portion 11 slightly 80 above the shoulder 18, one of said projections being shown at 19,—the horizontal faces 19^a of said projections being adapted to overlie the top button or base 20 (Figs. 2 and 3) to insure against upward displacement of the 85 lamp socket when the parts thereof are assembled within the casing. The side edges of said projections are likewise adapted for cooperative engagement by a suitable wrench or the like for effecting rotation of the cap in 90 fitting the latter to a threaded pipe end, which feature is particularly desirable when the cap is to be mounted within a husk or shade holder.

The body member 21 of the casing is also in 100

certain respects substantially like that shown in my application aforementioned, and includes a multiplicity of equally spaced integral radial projections 22 having their upper edges flush with the upper edge 23 of the body member. As shown, five of such projections 22 are provided, but if desired a sixth projection might be provided, as illustrated in dotted lines at 22^a in Fig. 3. Obviously the number of projections 22 and 10 bayonet grooves 14, 15 may be increased or decreased as desired,—provided that a cooperative relationship between the number and spacing of the grooves and projections is 15 maintained.

The projections 22 may be provided with slightly inclined surfaces 24 at the forward sides thereof with reference to the direction of rotation thereof during assembly with the 20 cap,—such surfaces being preferable to right-angled surfaces or shoulders for purposes of molding the body member, whereas the same likewise facilitate entry of said projections into the relatively shallow arms 14 of 25 the bayonet grooves to avoid wearing or chipping of the insulating shoulders during assembly of the casing parts.

The additional projection 25 which is unequally spaced from the projections 22 likewise preferably has its upper edge flush with the upper edge of the body member, and the radial or right angular side edge 26 thereof extends downwardly a distance which is preferably at least as great as the length of the 30 arms 15 of the bayonet grooves. The right hand side of projection 25 may if desired be inclined or beveled as indicated at 27, whereas the upper edge of said projection may be provided with a slight radius or curvature, as best illustrated at 28 in Fig. 6. Formed integrally with the projection 25 is 35 a thumb piece or operating button 29 having a ribbed or otherwise roughened surface 30, said button having a bevel or fillet 31 to increase the strength thereof and to facilitate 40 molding.

As will be apparent from the drawings, the wall 32 (Fig. 6) of the body member is of equal thickness throughout the whole circumference thereof. As shown said wall is 45 provided with a pair of slots 33, 34 arranged on opposite sides of the projection 25 and extending from the upper edge of the body member to points adjacent to the interior horizontal shoulder 21^b (Figs. 5 and 6). Also it will be noted that the slots 33, 34 are non-radial with respect to the longitudinal center of the body member 21, and said slots are further arranged to diverge outwardly with respect to each other from the inner surface 50 of the body wall.

The slots 33, 34 thus form a tongue or portion 21^a which is integral with the wall of the body member but flexible with respect thereto. Moreover, since the upper end of

portion 21^a is required to move inwardly an appreciable distance with the lower ends 33^a, 34^a of the slots 33, 34 as an approximate center of movement, it is obvious that such lower ends of the slots may be extremely narrow, 70 whereas the upper ends 33^b, 34^b of said slots are sufficiently wide to provide for the required degree of inward movement of tongue 21^a and projection 25 carried thereby.

Thus, as illustrated in Figs. 3 and 4 the 75 tongue 21^a when pressed inwardly is adapted to carry the projection 25 inwardly to a point substantially flush with the normal circumference of the body member 21. Thereupon the body member 21 may be freely telescoped into the cap 10 with projections 22 on the former engaging arms 15 of the bayonet grooves in the latter. Then by simply rotating the body member in a clockwise direction with respect to the cap the projections 22 enter the arms 14 of the respective bayonet grooves to hold the parts against endwise movement with respect to each other, while at the same time the side edge 26 of projection 25 snaps into engagement with 90 a full depth shoulder 15^a of an arm 15 of one of the bayonet grooves, as best illustrated in Fig. 4.

When the casing herein described is intended to enclose a keyless lamp socket, the 95 wall of the body member will be uninterrupted with the exception of the slots 33, 34. When a key socket or pull chain socket is to be enclosed within the casing the body member 21 may be notched, as indicated at 35 in the drawings,—it being noted that the notch 35 is circumferentially spaced a considerable distance from the slots 33, 34 to avoid unnecessary weakening of the casing wall. Similarly when the body member is provided with plural notches (not shown) to accomodate a push button socket, the angular position of said notches with respect to slots 33, 34 will be properly selected.

As will be apparent to those skilled in 110 the art, a body member 21 of the character illustrated in Figs. 1 to 6 may be initially molded to serve as a keyless lamp socket, as shown in Fig. 7,—said body member having a relatively thin wall portion 36 conforming to the desired shape of the notch 35. Said wall portion 36 may then, if desired, be sheared or knocked out to adapt the body member for use in conjunction with a pull chain or key type socket. Similar thin wall 115 portions or knock-outs may be provided to adapt the body portion of the casing for reception of a socket of the push button type.

The body member 21 is provided at the lower end thereof with a thread 37 which 120 may be formed thereon by the molding operation.

The insulating material of which the body member is formed is of substantially rigid 130 but slightly flexible character, such, for in-

stance, as the phenol-formaldehyde condensation product sold under the trade name of "bakelite". The cap member is also preferably formed of like insulating material, although if desired the cap member might be formed of another type of insulating material, or even of a suitable metal.

What I claim as new and desire to secure by Letters Patent is:

10 1. As an article of manufacture, a hollow casing comprising separable body and cap members at least one of said members being formed of substantially rigid but slightly flexible insulating material, one of said members having a multiplicity of equally spaced bayonet grooves formed therein, the other member having a multiplicity of equally spaced integral insulating projections adapted for cooperative engagement with said 20 bayonet grooves, said last mentioned member having an additional insulating projection unequally spaced from said first mentioned projections, said member having a slot on each side of said additional projection, and 25 said slots being non-radial with respect to the longitudinal center of said member and outwardly divergent with respect to each other whereby the walls of said slots cooperate to limit inward movement of said 30 additional projection, for the purpose set forth.

2. As an article of manufacture, a hollow casing comprising separable body and cap members each formed of substantially rigid but slightly flexible insulating material, one of said insulating members having a multiplicity of equally spaced bayonet grooves formed therein, the other insulating member having a circumferential wall of substantially uniform thickness and a multiplicity of equally spaced projections substantially flush with the upper edge thereof adapted for cooperative engagement with said bayonet grooves, said last mentioned member having an additional projection unequally spaced from said first mentioned projections, said member having slots in the wall thereof on each side of said additional projection, said slots being non-radical with respect to the longitudinal center of said member and outwardly divergent with respect to each other whereby the sides of said slots cooperate to limit inward bending of the wall portion therebetween, and a lamp socket base within the casing, said base having means to accommodate the aforementioned wall portion upon inward bending of the latter.

3. As an article of manufacture, a hollow casing comprising separable body and cap members each formed of substantially rigid but slightly flexible insulating material, one of said insulating members having a multiplicity of equally spaced bayonet grooves formed therein, the other insulating member having a circumferential wall of substan-

tially uniform thickness and a multiplicity of equally spaced projections substantially flush with the upper edge thereof adapted for cooperative engagement with said bayonet grooves, said last mentioned member having an additional and relatively longer projection unequally spaced from said first mentioned projections, said member having slots in the wall thereof on each side of said additional projection, said slots being non-radial with respect to the longitudinal center of said member and outwardly divergent with respect to each other whereby the sides of said slots cooperate to limit inward bending of the wall portion therebetween, a lamp socket base within the casing, said base having means to accommodate the aforementioned wall portion upon inward bending of the latter, and said wall having a notch therein to accommodate a switch actuating element, said notch being circumferentially spaced from said slots to avoid substantial weakening of the intermediate portions of the wall.

4. An electric lamp socket casing comprising separately molder cap and body members of insulating material, said cap member having a plurality of bayonet grooves formed in the wall thereof, said body member having a plurality of projections integral therewith and adapted to register with said grooves in substantially any rotary relation of said members, the wall of said body member having a pair of adjacent slots which diverge outwardly with respect to each other from the inner surface of said wall, an additional projection carried by said body member between said slots, said projections cooperating jointly with said bayonet grooves to lock said cap and body members against relative rotary and longitudinal movements, and the walls of said slots serving to limit the inward flexure of that portion of the body member located therebetween.

5. An electric lamp socket casing comprising separately molded cap and body members of insulating material, said cap member having a plurality of bayonet grooves formed in the inner wall thereof, said body member having a plurality of projections integral therewith and adapted to register with said grooves in substantially any rotary relation of said members, the wall of said body member having a pair of spaced substantially vertical slots extending from the upper edge thereof, said slots diverging outwardly with respect to each other from the inner surface of said wall and the walls of each slot diverging slightly from the lower ends thereof, an additional projection carried by said body member between said slots, said projections cooperating jointly with said bayonet grooves to lock said cap and body members against relative rotary and longitudinal movements and the walls of said di-

verging slots serving to limit the inward flexure of that portion of the body member located therebetween.

6. In an electric lamp socket casing, in combination, a molded hollow body member of insulating material, said body member having a plurality of integral radial projections substantially flush with the upper edge thereof and equally spaced from each other, 10 said body member having a non-radial slot extending from the upper edge thereof to provide for flexure of an adjacent portion of said body member, the walls of said slot coacting to limit the inward flexure of said portion, and an additional radial projection 15 on said portion adjacent to said slot, said last mentioned projection being unequally spaced from said first mentioned projections.

7. In an electric lamp socket casing, in combination, a molded hollow body member of insulating material, said body member having a plurality of integral radial projections substantially flush with the upper edge thereof and equally spaced from each other, 20 said body member having a pair of circumferentially spaced slots or passages extending substantially vertically from the upper edge thereof to provide for flexure of the wall portion located therebetween, said 25 slots diverging outwardly with respect to each other from the inner surface of said body member and the opposed walls of said slots coacting to limit inward flexure of said portion of the body member, and an additional 30 radial projection on said flexible portion, said last mentioned projection being unequally spaced from said first mentioned projections.

8. An electric lamp socket or the like comprising a casing having independent cap and body members formed of substantially rigid but slightly flexible insulating material, and latching means for securing said members together in substantially any relative rotary 45 position thereof and serving to hold the same together against endwise separation and relative rotary displacement, said latching means comprising shouldered insulating portions integral with the respective cap and 50 body members and adapted for positive interlocking engagement with each other, a shouldered portion on one of said members being formed to require yielding movement thereof for effecting such interlocking engagement, said last mentioned member having a pair of slots through the wall thereof on opposite sides of said shouldered portion, and said slots being outwardly divergent with respect to each other to positively 55 limit inward bending of the tongue formed thereby.

9. A locking joint for insulating members consisting of a hollow insulating body member and an insulating cap member, said cap member having a plurality of equally spaced

substantially L-shaped notches in the inner wall thereof, the open ends of said notches being flush with the lower edge of said cap, said body member having a plurality of equally spaced integral lateral projections 70 adjacent to the upper edge thereof, said projections being adapted to jointly register with a corresponding group of notches in said cap member whereby said members may be joined by sequential telescopic movement 75 and partial relative rotation thereof, said body member having a non-radial slot extending downwardly from the upper edge thereof to provide for flexure of a portion of the body member adjacent thereto, the 80 walls of said slot coacting to limit the inward flexure of said portion, and another lateral projection on said flexible portion unequally spaced from said first mentioned projections and adapted upon such relative rotation of said members to snap into engagement with a shoulder of one of said notches whereby said members are positively locked 85 against relative rotary or longitudinal movements.

In witness whereof, I have hereunto subscribed my name,

WILLIAM C. TREGONING.
